SLIP

Michael Polsky, Brooklyn, N. Y.

Application June 4, 1935, Serial No. 24,842

1 Claim. (Cl. 2-73)

This invention relates to women's apparel and refers more particularly to garments for feminine wear, such as, evening gowns, slips, chemises, night gowns, and the like.

5 An object of the present invention is the provision of a garment which is also devoid of vertical side seams and the seams of which consist of one or more slanting oblique seams extending from the top to the bottom of the garment.

10 Another object is the provision of an under-garment which is stretchable to a very large extent and which is adapted to fit any type of figure.

15 The above and other objects of this invention may be realized through the provision of an under-garment consisting of one or more parts, the edges of which are sewn together to form seams extending diagonally across either the front or the back of the garment.

20 The invention will appear more clearly from the following detailed description when taken in connection with the accompanying drawing showing by way of example only, preferred embodiments of the inventive idea.

25 In the drawing:

Figure 1 is a front view of a slip disclosing an embodiment of the present invention.

Figure 2 is a section along the line 3-3 of Figure 1.

30 Figure 3 illustrates the method of sewing the slip shown in Figure 1.

The undergarment illustrated in Figures 1, 2 and 3 of the drawing consists of a single piece 7 which is cut in any suitable manner out of a large piece of textile fabric.

35 The cut piece 7 comprises two diagonal edges 8 and 9, the bottom edge 10 and the usual triangular upper pieces 11, 12, 13 and 14 which form the V-neck. A shoulder strap 15 is sewn to the pieces 13 and 12 while the piece 14 is connected with the piece 11 by the shoulder strap 16.

The under-garment when completed comprises a single seam 8, 9 which extends diagonally across the front portion of the garment from the top left hand edge to the bottom right hand edge. The under-garment has no vertical side seams 5 at all and is stretchable to a very large extent due to the absence of the vertical seams and the provision of a single diagonal seam.

The garments manufactured according to the present invention may be made of cotton, rayon, 10 silk, the combination satin-cellulose acetate or any other suitable material. They will eliminate a V-back. The garments have a maximum stretch around the bust and hips and will fit any figure.

15 The single piece of material as illustrated in Figure 3 is substantially of trapezoidal shape, the two sides of the trapezoid extending substantially in the direction of the warp and being joined together to form a single seam, the bias 20 of the material extending substantially circumferentially of the body.

What is claimed is:

A feminine undergarment in the form of a slip extending from the arm pits to substantially 25 the knees and suspended from the shoulders by shoulder straps, said garment being formed of a single panel or piece of substantially stretchable textile material of trapezoidal shape, the base of the trapezoid forming the lower edge of the garment, the top of the trapezoid forming the top 30 of the garment, and the two sides of the trapezoid extending substantially in the direction of the warp and being joined together to form a single seam, said seam extending diagonally 35 across the garment from one side adjacent the top and adjacent an arm pit to the other side adjacent the bottom, the bias of the material extending substantially circumferentially of the body.

40 MICHAEL POLSKY.
